UNITED STATES PATENT OFFICE

HERMAN C. HUEGLIN, OF CHICAGO, ILLINOIS, ASSIGNOR TO FEDERAL MERCHANDISE COMPANY, OF CHICAGO, ILLINOIS, A CORPORATION OF ILLINOIS

VENTILATOR

Application filed July 22, 1929. Serial No. 380,003.

This invention relates to ventilating means, more particularly to ventilating means of the type adapted to be mounted in a window in a residence and operated to force air out through that window.

Ventilating means of this type have been devised heretofore, those devices usually comprising a metallic panel upon which an electric fan is mounted. This fan is frequently of the so-called ring mount type, that is it comprises a ring-like member having brackets extending outward and backward therefrom to support the motor of the fan.

15 The fan blades are rotated within the area defined by the ring, which ring also serves as a support for mounting the fan in the panel.

Panels of this type are subject to two general objections, the first of which is overcome 20 by making the panel adjustable. If the panel is not adjustable, a large number of sizes must be carried in stock so that the ventilating means may be fit into the various sizes of windows encountered in residences and the like.

25 Panels of this type are subject to further criticism that the solid nature of the supporting panel of the ventilating means blocks off a goodly portion of the window space with the consequent darkening of the room in which the device is employed.

In my present invention I have overcome 30 both of these objections, first by making the panel upon which the fan is mounted adjustable as to length so that it may be accommodated into the various size windows encountered in residences.

I have furthermore made the panel of 35 transparent material, preferably glass, so that its insertion in a window does not obstruct the entrance of light through the window and consequently does not darken the room in which the device is used. In my Patent No. 1,784,234 issued December 9, 1930 40 I disclose a similar glass panel capable of being adjustably mounted in a window frame in the manner hereinafter described.

In my copending application, Serial No. 289,573, filed June 30, 1928, I disclosed a ventilating means in which an adjustable panel

was adapted to be mounted in a window, into the space immediately above the lower sash of the window.

This construction permitted the upper sash of the window to be operated in a normal manner, so that the window could be fully closed during storms and the like, without removing the ventilating means from the window.

A ventilating device of this kind is subject 55 to the criticisms that since it is permanently mounted in the track in which the lower sash is raised, the maximum distance that that sash can be raised is thereby reduced. This is particularly objectionable since it makes 60 it extremely difficult for the housewife to clean the inside surface of the upper sash as well as restricting the opening that it is possible to obtain by adjustment of the lower sash.

In my present invention I have provided a new and improved ventilating means which overcomes this objection by providing a mounting which permits adjustment of the 65 ventilating means in and out of the window, that is permits mounting the ventilating means with its panel parallel to the plane of the window sash, and further permits adjustment of that panel at right angles to its 70 plane and to the plane of the window sash. This adjustment can be made without demounting the ventilating means from the window. By this arrangement the ventilating panel can be drawn inward into the room 75 out of the track of the lower sash, thereby 80 permitting that sash to be raised to its full extent for cleaning or any other desired purposes.

In the preferred embodiment of the invention the glass panel and its supporting frame is formed as a standard unit of lengths adapted to fit it into the average window encountered in residence and the like. The panel is arranged to be supported in a flanged mounting bracket which engages the upper and lower surfaces of the panel frame and which are adjustable lengthwise of the frame to compensate for slight differences in the width of the windows in which the device is to be mounted. These brackets may be made in 85 90 95 100

varying lengths so that the amount of adjustment lengthwise of the panel can be varied to suit the varied conditions encountered.

The mounting brackets are provided with flanges depending at right angles to the plane of the ventilating panel, and slots are provided in these flanges.

The panel is mounted in the window by a plate attached to the window frame on the inside of the track in which the lower sash operates. These plates fit between the window frame and the flanges of the mounting brackets, and contain threaded openings into which thumb screws are registered, those thumb screws projecting through transverse slots in the flanges of the mounting brackets.

By this arrangement, the panel is supported rigidly in the window, and can be adjusted in and out over the track in which the lower sash slides by loosening of the thumb screw and sliding the flanges of the mounting bracket thereon. The panel mounting arrangement of the present invention is also shown in my copending application which has now issued as Patent No. 1,784,234.

Preferably the panel is set so that it lies just inside of the upper sash of the window when that sash is in its upper-most position, so that the sash may be freely raised and lowered without striking against or being interfered with by the ventilating means. This permits the upper sash to be tightly closed when storms are encountered.

By this preferred adjustment of the position of the ventilating panel the lower sash is limited in its movement as heretofore, however in instances where it is desired to open the lower sash to its fullest extent, the ventilating means can be backed into the room out of the path of the lower sash by loosening the thumb screws and sliding the flanges of the brackets thereon. The weight of the panel and fan mounted on it is at all times supported by the thumb screws even when they are loosened so that lateral adjustment of the panel in a direction at right angles to the plane of the window sash can be easily and conveniently made.

In the preferred embodiment of my invention I employ a fan of the ring mounting type, and support that fan in the framework of the transparent panel so that it is supported entirely free of the glass or other transparent material used in the panel. That is, the frame work of the transparent panel serves as a mounting support for the ring of the fan mechanism, and instead of being supported on the glass, that ring serves as a support for the glass or other transparent material of which this panel might be constructed.

This construction rigidly mounts the fan mechanism to the panel and eliminates the danger of the fan falling and being damaged

should the transparent material in the panel become broken.

Now to acquaint those skilled in the art with the teachings of my invention, reference is made to the accompanying drawings in which I have illustrated a preferred embodiment of it and in which;

Figure 1 is an elevation view of the ventilating means mounted in a window;

Figure 2 is a cross-sectional view taken along the lines 2—2 of Figure 1 with the central portion broken away;

Figure 3 is an elevation view of the transparent panel and its frame with the fan mounted thereon;

Figure 4 is a perspective view of a portion of the mounting bracket showing the details of its construction;

Figure 5 is a cross-sectional view taken along the lines 5—5 of Figure 3, and

Figure 6 is a cross-sectional view taken substantially along the lines 6—6 of Figure 3.

By reference to the drawings in more detail it will be seen that the panel 1 is supported in the one end of the rectangular framework 2, and that the fan indicated generally at 3, is supported in the center of this framework. A second panel 4 is mounted in the framework 2, on the opposite side of the fan mechanism 3.

This assembly therefore comprises a unitary structure consisting of a generally rectangular panel having a fan mounted opposite a central opening in the panel. The framework indicated generally at 2 consists of a rectangular member 6 having a flange 7 disposed at its outside edge at right angles to the main part of the frame. A second rectangular member 8 is fitted within the rectangle defined by the extreme edge of the flange 7, and held onto the member 6 by screws 9 projecting through the member 8 and registering with threaded openings in the bosses 10 attached to the inside surface of the member 6. These bosses may be attached by soldering, welding or any other preferred method.

The member 6 and 8 and the flange 7 on the member 6 together define a framework of U-shaped cross-section, the open end of the U being disposed inwardly of the frame.

The ring of the fan 3 is supported in this framework by metallic members 12 which are supported in the framework by screws 11 projecting through the member 8 into threaded openings in the members 12. There are two of these members 12, one disposed in the upper section of the frame 2 and one in the lower section, both being centrally located in their respective sections. Each member 12 is supported in the frame by two screws 11, so that the rings of the fan can thereby be rigidly supported in the frame.

The fan 3 which is preferably of the type

shown in my above mentioned copending application, although other similar fans may be substituted therefor, comprises the ring member 20 which contains spider arms 21 radially extending from the inside edge of the ring 20 to the motor support cap 22. Preferably the ring 20 and the spider arms 21 and motor support cap 22 are cast as an integral unit, preferably aluminum although 10 brass or other suitable material might be substituted therefor. The ring 20 is provided with a shoulder 23 which fits against the innermost edge of the mounting member 12.

To attach the ring 20 to the mounting member 12 an auxiliary ring 24, containing the flange 25 and the threaded openings 26, is fitted on the opposite side of the member 12 and the screws 27 project through the member 20, the member 12, into the threaded opening 26 of the member 24 to attach the fan to the framework.

The shoulders 23 and 25 when butted together form a rectangular slot in the periphery of the rings 20 and 24, into which slots 25 the mounting member 12 and the panel members 1 and 4 are fitted.

Preferably the panel members 1 and 4 which are made of glass or other suitable transparent material, are prevented from 30 coming into contact with the metallic framework by the soft spacers 30 and 31 which are disposed within the open end of the U-frame respectively adjacent to the members 6 and 8.

Similar soft members 32 and 33 are disposed within the slot formed in the rings 20 and 24 of the fan mounting so that the panel members 1 and 4 are prevented from coming in contact with these metal members.

These soft spacing members 30 to 33, inclusive, may be made of cork, felt, fiber, or any other preferred relatively soft material, their purpose being to cushion the glass panel members 1 and 4 to prevent them coming in 45 contact with the metal framework and to prevent breakage of the glass due to expansion and contraction of that framework with temperature changes and the like.

It will be noted in Figure 2 that the frame member 8 is disposed on the outside of the window and the frame member 6 on the inside. By this arrangement, no screw heads or other blemishes are exposed to view from the room side of the framework so that that 55 framework presents a pleasing appearance to those within the room. The framework may be plated and polished or painted to match the color scheme of the room in which it is used, the smooth surfaces of the frame facilitating this operation.

The unit so constructed is rigid yet sufficiently light in weight to permit it being easily handled. The fan is supported on the framework independently of the glass panel 65 members so that the assembly may be made

in the factory and shipped to the customer without danger of breaking the glass panel during shipping.

To mount the panel 2 in the window of a residence, and to provide for adjustment of 70 the length of this panel to meet the width of the window in which it is to be mounted, I have provided mounting brackets 40 and 41 which are identical in every respect and which are disposed on opposite ends of the panel 75 member 2.

The bracket 40 comprises the flat face 44 which is adapted to fit on the inside face of the panel member 2. This face 44 has the rib 80 45 formed in it to stiffen it.

At the top and bottom edges of the face 44, a flange 46 is projected at right angles to the plane of the face 44, that flange terminating in an upward turned edge 47 disposed parallel to the plane of the face 44 and at right angles to the flange 46. These flanges form a C clamp-like member which fits over the top and bottom edges of the panel 2, supporting that panel in the bracket.

This support permits the bracket member 90 40 to be slid along in a plane of the panel 2.

The bracket member 40 is also provided with a flange portion 48 disposed at right angles to the plane of the face 44. This member 48 is provided with a plurality of slots 95 49 disposed also at right angles to the plane of the face 44.

The brackets 40 and 41 are attached to the fan supporting panel by placing the face 44 on the inside face of the panel with the flange 46 engaging the top or bottom edge of the panel and the projection 47 engaging the outside face of the panel adjacent that edge. The corresponding flange and panel on the opposite ends of the brackets, not shown, engage 100 the opposite edge of the panel in a similar manner. The flanges 48 project inward from the inside face of the fan supporting panel 2 to mount the device in a window.

The panel is adjusted to the correct length 110 to fit into the window by sliding the brackets 40 and 41 along on the panel so that the face 44 projects beyond the end of the panel 2 sufficiently to cover the space intervening between the ends of that panel and the sides of 115 the window frame.

I propose to supply the mounting brackets 40 and 41 in several different sizes, that is with the panel portion 44 of different widths, so that a fan supporting panel 2 of standard 120 length can be fitted into any window likely to be encountered in residences. With the panels 2 available in a few standard sizes and the brackets 40 and 41 available in several sizes interchangeable with the various panels only a small stock of parts will be required to fit the ventilator into any one of the various size windows encountered.

To facilitate mounting the ventilator in a window I have provided the mounting plate 130

50 which comprises a rectangular metallic bar perforated with holes 51 which are countersunk to permit attaching the bar to the frame of a window with flat head screws 5 which when turned up tight will be flush with the face of the plate. The plates 50 are also provided with threaded holes 52 which are spaced to register with the slots 49 in the mounting flange 48 of the bracket.

10 As will be best seen in Figures 1 and 2 the mounting plates 50 are attached to the inside window stop 54 preferably by flat head wooden screws, not shown.

15 These plates 50 are attached to the stop 54 at a point sufficiently far from the inside face of the lower sash 57 to permit the panel 2 to clear that face of the sash when the ventilator is drawn in to its fullest extent.

20 The ventilator is mounted upon the mounting plate 50 thumb screws 53 are projected through the slots 49 in the mounting flange 48 and into the threaded openings 52 in the mounting plate 50. Preferably two thumb screws are provided at each end of the ventilating panel, one near the top and one near the bottom edge of it.

25 After the thumb screws 53 have been inserted and before they are tightened up the position of the ventilator can be adjusted by moving the panel in and out, the thumb screw 53 sliding in the slot 49 to permit this adjustment. After the panel has been positioned in the desired location, the thumb screws 53 are turned tight to securely lock the panel in place.

30 Preferably the ventilator is adjusted in the window so that the outside face of the panel 2 is disposed just inside of the inside face of the upper sash 56 of the window, that is with the ends of the panel 2 disposed in the plane of the parting stops 55 which define the inner edge of the groove in which the upper sash runs. This location of the ventilating panel permits the upper sash to be 35 raised and lowered in the usual manner without any interference from the ventilating panel.

35 In Figure 2, by the solid lines I have indicated the maximum outward position to which the ventilating panel can be adjusted. In this position the panel is disposed over the upper surface of the upper sash, which of course must be lowered, and the sash cannot therefore be closed without readjustment of the position of the ventilating panel.

40 The dotted lines in Figure 2 indicates a maximum inward position to which the ventilating panel can be adjusted. It will be noted that this is inside of the inside face of the lower sash 57 so that that sash may be raised or lowered to its fullest extent without interference from the ventilating panel.

45 This inside adjustment of the ventilator permits the full raising and lowering of the window sash, a feature which is particularly

advantageous when it is necessary to wash the inside surface of the glass in the window sash. Heretofore this operation has been difficult where ventilating panels were installed in the window since those panels did not permit the lower sash to be raised completely to the top of the window and frequently did not permit the upper sash to be completely closed.

50 When the thumb screws 53 are loosened to permit lateral adjustment of the ventilating panel in the window the weight of that panel is still supported by the mounting plates 50 and the thumb screws 53 so that this lateral adjustment may be easily made.

55 Ventilating means constructed in accordance with the teachings of my invention presents a pleasing appearance both from the inside and the outside of the room in which it is to be used. The transparent panels of the ventilator permits its use in a window without blocking out an appreciable amount of light admitted to the room through that window.

60 While I have illustrated a preferred embodiment of my invention, I have done so by way of example only as there are many modifications and adaptations which can be made by one skilled in the art without departing from the teachings of the invention.

65 Having thus complied with the statutes as shown and described a preferred embodiment of my invention, what I consider new and desire to have protected by Letters Patent is pointed out in the appended claims.

70 What is claimed is:

1. A ventilating means comprising a panel, means for adjusting the length of the panel to fit it into a window having upper and lower slideable sash, and means for mounting the panel in the window, said mounting means including means for adjusting the panel through movements at right angles to the window into the plane of either sash and out of the planes of both and for supporting the panel while it is being moved.

75 2. In a ventilating device, a panel supporting a ventilating fan, brackets slidably attached to said panel to adjust it to fit into a window frame, flanges on said brackets disposed at right angles to the plane of said panel, and having slots also disposed at right angles to said panel, plates adapted to be mounted on a window frame and having threaded openings adapted to receive thumb screws projected through said slots to adjustably mount said flanges on said plates to thereby mount said panel in a window casing and to permit adjustment of it in and out of the plane of the window.

80 3. In a ventilating device, a framework surrounding a transparent panel member, a ventilating fan mounted in said framework independently of said panel member, a bracket slidably mounted on said framework, a

flange on said bracket having slots at right angles to said framework, a plate attached to a support, and thumb screws threaded into said plate and projecting through said slots

5 to mount said bracket on said support.

4. A bracket comprising a ribbed planar portion having flanges extending from its opposite sides to form supporting channels, a flange having a plurality of slots, said

10 flange projecting from one edge of said planar portion at right angles thereto, a mounting plate having threaded openings, said plate being rigidly attached to a support, a panel supported in said channels, and means ex-

15 tending through said slots into said threaded plate openings for adjustably mounting said bracket and the panel supported thereby on said support.

5. The combination of a framework comprising a rectangle formed of members of L-section disposed with their open sides extending inwardly of the rectangle, and a second rectangle disposed within said open sides and composed of flat members, with a

20 pair of supporting brackets disposed between the members of said frame and projecting inwardly of said rectangles, a fan, supporting rings therefor, said rings engaging opposite sides of said supporting brackets to

25 hold the fan within said framework, and a transparent panel in said frame on each side of said fan, said panels being held in said frame by the joint support of said frame mounting rings and frame members.

6. A ventilator adapted for mounting in a window having an upper and a lower sash slideable in grooves defined by stop strips, comprising a transparent panel member supported in a frame in which frame a fan unit

30 is also mounted, mounting plates adapted to be rigidly attached to the stop strips which partly define the grooves in which the lower sash slides, brackets mounted on said plates and slideable thereon at right angles to said

35 grooves, and means on said brackets engaging said panel to support it in said window.

7. A ventilator adapted for mounting in a window having an upper and a lower sash slideable in grooves defined by stop strips,

40 comprising a transparent panel member supported in a frame in which frame a fan unit is also mounted, mounting plates adapted to be rigidly attached to the stop strips which define the grooves in which the lower sash

45 slides, and mounting brackets having a flange adapted to lie across said plates and grooves and to be slidably attached to the plates, and means on said brackets engaging said panel to support it in said window.

50 In witness whereof I hereunto subscribe my name this 19th day of July, 1929.

HERMAN C. HUEGLIN.
